FLAG STANDARD

Harry M. Olson, Nora Springs, Iowa

Application June 30, 1941, Serial No. 400,500

2 Claims. (Cl. 116—173)

This invention appertains to new and useful improvements in means for conveniently and properly displaying flags.

The principal object of the present invention is to provide a flag support for supporting a flag and staff in a definite position, said support being provided with adjusting means whereby the flag supporting upright can be easily adjusted and held in the desired upright position.

Various other important objects and advantages of the invention will become apparent to the reader of the following specification.

In the drawings:

Figure 1 is a side elevational view of the standard in useful position.

Figure 2 is a section on the line 2—2 of Figure 1.

Figure 3 is a fragmentary vertical sectional view showing the means for connecting the

Figure 4 is a fragmentary vertical sectional view through the upper section of the pole.

Figure 5 is a fragmentary detailed sectional view showing the means for connecting the pole section.

Figure 6 is a fragmentary side elevational view showing the lower portion of the anchor attached sleeve.

Figure 7 is an edge elevational view of the anchor element.

Figure 8 is a side elevational view of the assembly with parts broken away, showing the pole sections disposed in a case.

Referring to the drawings wherein like numerals designate like parts, it can be seen that the invention includes a pair of tubular pole sections 5 and 6, a flag 7 being secured to the section 6. The upper end of the section 6 has a knob or other ornament 8 secured in place by a bolt 8' having its head fastened in the upper end of the section 6 of the pole with its threaded end projecting from said upper end and an eyelet 7' is secured in the upper end of the hem 7" formed at the inner end edge of the flag. This tubular hem fits over the upper portion of the upper section of the pole with the eyelet resting on the upper end of the upper section and the knob 8 holds the eyelet between itself and said upper end of the pole, see Figure 4.

The lower end of the section 5 is disposed into a sleeve 9 closed at its bottom and provided with a depending hook 10. The upper portion of this sleeve 9 is provided with threads 11 to accommodate a burr 12 having a concaved skirt 13 for embracing the convexed apex portion 14

of a conical shell 15. The apex portion of the shell 15 has an oversize opening therein for receiving the sleeve 9.

As shown in Figure 3, numeral 16 denotes the surface of the ground and numeral 17 denotes an opening formed therein and in which a deposit of concrete 18 is located having embedded therein a vertically disposed rod 19 on which are laterally disposed fingers 20. This element defines an anchor and is formed at its upper end with an eye 19' to which is attachable the hook 10.

It can be seen that the upper section 6 can be connected to the lower section 5 by a pin 21 which is fastened in any suitable manner in one section of the pole with a part projecting from such section and this projecting part of the pin has a friction fit in the upper section, as shown in Figure 5. Thus the two sections are detachably connected together by the pin. The lower end of the section 5 is placed in the sleeve 9 and the burr or nut 12 can be tightened down onto the convexed upper portion 14 of the shell 15 to hold the pole sections 5 and 6 in vertical position. By tightening down on the burr 12, the conical shell 15 will be snugly clamped against the ground. Obviously, this eliminates sockets and the like in pavements and other places which frequently fill up with earth or are hard to reach in winter time when there is snow and ice about.

In storing the apparatus above described, it is to be understood that the anchor 18, 19 is left in the ground or pavement while the rest of the structure is taken away and stored. In connection with the storage of the structure, a special case generally referred to by numeral 22 is provided. This case consists of an elongated shell having a longitudinally extending partition 23 dividing the interior into a pair of elongated pockets, one of which is intended to receive the pole section 5 and the other to receive the pole section 6 when the flag 7 has been wound thereon. It will be observed, that the first-mentioned pocket is opened at its bottom and closed at its top so that the same be disposed over the section 5 while the other pocket is closed at its bottom and open at its top so that the upper section 6 can be inserted therein from the top thereof.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. Flag supporting means comprising a ground anchor, a shell having a wide base for engaging the ground around the anchor, a sleeve passing through the top of the shell, means for detachably connecting the lower end of the sleeve to the anchor, clamping means for clamping the sleeve to the upper end of the shell and a flag pole having its lower end seated in the sleeve.
2. Flag supporting means comprising a ground anchor, a shell having a wide base for engaging

the ground around the anchor, said shell having an opening in the top, a sleeve passing through the opening and having its upper portion exteriorly threaded, a nut engaging the threaded part and having a lower flange for engaging the upper end of the shell for clamping the sleeve to the shell, said sleeve being adapted to receive the lower end of a flag pole and means for detachably connecting the lower end of the sleeve to the anchor.

10 HARRY M. OLSON.
